(57) **CLAIM**

The ornamental design for a termination device for a concrete reinforcement bar, as shown and described.

DESCRIPTION

FIG. 1 is an exploded perspective view of a termination device for a concrete reinforcement bar in accordance with my invention;

FIG. 2 is an environmental exploded side view of FIG. 1 shown placed on a concrete reinforcement bar;

FIG. 3 is a section cut view of the termination device for a concrete reinforcement bar taken along line 3-3 of FIG. 2; FIG. 4 is a compressed side view of the termination device for a concrete reinforcement bar; and,

FIG. 5 is a section cut view of the termination device for a concrete reinforcement bar taken along line 5-5 of FIG. 4.

1 Claim, 5 Drawing Sheets
